(57) **CLAIM**

The ornamental design for a bar code scanner stand, as shown and described.

DESCRIPTION

FIG. 1 is a perspective view of the front and left sides of a bar code scanner stand showing our new design;

FIG. 2 is a right side view thereof, the left side being a mirror image;

FIG. 3 is a front view thereof;

FIG. 4 is a back view thereof;

FIG. 5 is a bottom view thereof; and,

FIG. 6 is a top view thereof.

The broken lines shown in FIGS. 1-6 are for illustrative purposes only and form no part of the claimed design.
